UNITED STATES PATENT OFFICE.

ADELINE J. CORSCADEN, OF PHILADELPHIA, PENNSYLVANIA, ADMINISTRATRIX OF THOMAS CORSCADEN, DECEASED.

DIE FOR SHAPING BLANKS FOR PULLEY-SPOKES.

SPECIFICATION forming part of Letters Patent No. 630,777, dated August 8, 1899.

Application filed October 26, 1898, Serial No. 694,599. (No model.)

To all whom it may concern:

Be it known that THOMAS CORSCADEN, deceased, formerly of the city and county of Philadelphia, State of Pennsylvania, did invent an Improvement in Dies for Shaping Blanks for Pulley-Spokes, of which the following is a specification.

This invention has reference to dies for shaping blanks for pulley-spokes; and it consists of certain improvements which are fully set forth in the following specification and shown in the accompanying drawings, which form a part thereof.

The invention comprehends certain improvements in die structures adapted to form or shape spoke-blanks suitable for pulleys of the character shown in Patent No. 595,559, dated December 14, 1897. In sheet-metal pulleys of the form shown in said patent the spoke-arms are made from a sheet-blank divided longitudinally to a point adjacent to one end and the several parts spread so as to radiate from a hub-center.

The improvements comprehend dies for severing portions of the blank, whereby it is brought to a condition which permits it to be subsequently shaped and formed. In carrying out the invention two die structures are provided—namely, an upper and lower—which by coaction shall clamp the blank and properly shear and bend the same. The lower die structure is provided with two blades more or less parallel and with an interposed spring-actuated floor, and also with stripper-bars, between which and the shearing-blades the blank to be treated is placed. The said die structure may further be provided with suitable guides for properly registering the blank in position. The upper die structure comprises a central shearing and forming die which operates in conjunction with the two shearing-blades of the lower die structure and also with the movable floor in the manner hereinafter described. This upper die structure may, furthermore, be provided with two outer shearing-blades for trimming the outer edges of the blank, though this latter feature may be omitted, if desired. The operation of these dies upon a blank is to trim the blank into the requisite shape and at the same time to divide the same by two substantially par-

allel slits almost the entire length of the blank and simultaneously therewith depress the strip or tongue of the blank intermediate of the two slits, so that the blank is subdivided without the removal of any metal intermediate of the three strips or arms so formed, which subsequently form the radiating spoke-arms. In the subsequent operations of forming the spoke-arms the three strips or arms are brought into the same plane and treated to the action of the dies, which spread the arms and curve the hub portion, but which form no part of this invention. The improvements will be better understood by reference to the accompanying drawings, in which—

Figure 1 is an inverted plan view of the upper die structure. Fig. 2 is a plan view of the lower die structure. Fig. 3 is a side elevation of the dies complete. Fig. 4 is a cross-section of same on line $\alpha\alpha$. Fig. 5 is a plan view of the blank after being treated. Fig. 6 is a longitudinal section through the blank on line $y\gamma$, and Fig. 7 is a transverse section through the blank on line $z\zeta$.

A is the main frame of the lower die structure and is provided with two longitudinal shearing-dies B B, bolted in position by transverse bolts b. These dies B B may be parallel, if so desired, or may be arranged at a slight incline and, furthermore, be somewhat tapered in plan view, as shown in Fig. 2, so as to taper the width of the three longitudinally-sheared sections or arms of the blank, as shown in Fig. 5. Interposed between the dies B B is a movable floor C', the upward movement of which is limited by bolts L L, while the upward thrust to said floor is imparted by means of flanges c and spring J, arranged in the lower part of the main frame A and held in position by a longitudinal plate K. The bolts L have heads which cause them to move with the floor, and also have nuts at the bottom for adjustment and to catch upon the under side of the frame or base A, as shown, to limit the upward movement of the floor under the action of the springs. The movable floor C' acts in a measure as a movable jaw for the lower die structure in the manner to be hereinafter described. Arranged above each of the shearing-dies B B are stripper-blocks B' B', said stripper-blocks being

supported at each end in the cross-blades F F, to which they are riveted at f'. This enables the plate after being sheared to be readily stripped from the upper die, to be now described.

H is the main frame of the upper die structure and has secured to it the central shearing-die C, which is of less length than the dies B B and is adapted to operate in connection with their adjacent faces for the purpose of shearing the blank T and the forming the intermediate arm or tongue T'. It will also be observed that this die C coacts with the movable floor C', so that in cutting the blank and depressing it the said tongue or arm T' is caused to lie parallel to the upper portion of the blank. This prevents what would otherwise be a considerable displacement of this part of said blank. It is to be understood that while the said die C shears the blank completely at one end its other end is at a considerable distance from the opposite edge of the blank, so that there is a transverse portion left uncut corresponding to the hub-section of the blank in the latter formation. This is clearly shown in Fig. 5. The severance between the tongue T' and the main portion of the blank is such that there is no removal of metal between the tongue and its adjacent parts, but the latter is simply depressed to a slight extent to insure a clean cut and severance, and thereby obviate the weakness which would occur adjacent to the hub by the removal of the metal. The end of the die C adjacent to the hub end of the blank is somewhat rounded, so as to form a curved depression between the tongue and the blank, as indicated in Fig. 6.

I are two side shearing-blades which are also bolted to the upper main frame H by transverse bolts i, the said blades I operating in conjunction with the outer edges of the dies B B. The function of these blades I is to shear the outer lateral edges of the blank to properly taper the arms formed thereon. While preferring said construction, it is not essential that said arms shall be tapered, for in small pulleys the tapering would hardly be perceptible on account of the short length of the arms, and in this case it is evident that the dies I might be omitted, if so desired. They are advantageous, however, in that the blanks do not have to be so accurately made before being inserted in the dies, and in using the dies we are insured that the width of the several arms will accurately conform to the requirements.

The upper die structure is recessed between the dies C and I to form spaces in which the stripper-bars B' are received, as is clearly shown in Fig. 4. The stripper-bars should be placed a distance sufficiently above the upper surface of the dies B so that when the movable floor C' raises the blank the tongue T' may be at an elevation sufficient to clear the upper surface of the dies B. Said blank

may be pushed laterally out of the dies. This construction is illustrated in Fig. 4.

The ends of the lower die structure are provided with plates F F, which are notched, as shown in Fig. 2, to receive the upper die structure and more or less guide the same. One of these plates F at one end of the dies is provided with a series of apertures f. Interposed between the stripper-bars B' and the tops of the dies B is a guide-plate also having a series of apertures r, so located that a pin S thrust down through the apertures f and the corresponding apertures of the plate R will adjust the said guide-plate longitudinally in position to make proper widths of the uncut portion of the blank to correspond to the right width suitable for the hub portions. It will be observed that these holes f and r are arranged in pairs and are somewhat out of alignment, some pairs being out of alignment to a greater extent than others, and from this it is seen that it is only necessary to shift the plate to the required degree by about one-eighth or one-fourth of an inch to bring another pair of holes f' r into alignment, when the pin S may be thrust through them and the adjustment of the guide R thus secured in place. To secure longer or shorter arms to the blank, it is only necessary to insert blanks of greater or less length and adjust them always to the guide-plate R, in which case the requisite width of the hub portion will be secured and the ends of the arms will be according to the previously-prepared length of blank. This guide-plate R is adjustable and overlaps the outer cutting edges of the dies B, longitudinally considered, while lying in substantial alignment with said cutting edges, but lies wholly to one end of the inner cutting edges of the said dies B, which coact with the upper central die C, so as to insure a portion of one end of the blank remaining unsplit. It will be further seen that the apertures r are out of transverse alignment upon the guide R, while the apertures f in the plate F correspond to those in the guide, longitudinally considered, but out of transverse alignment with them, transversely considered, the said apertures in the guide and plate being in the direction of the movement of the dies. The pin S may thus lock the guide R in various adjustments relatively to the plate F and the dies proper. Attention is further called to the fact that when the blades B and I are designed for tapering the arms and used with the portion of the dies which corresponds to the hub part of the blank—namely, that portion to the right of the die C in Figs. 1 and 2—they are so shaped as not to taper the blank at the parts t t, Fig. 5, since these parts when curved into a semicylinder must be parallel and form the division-line of the hub. The shapes of the dies B I for this purpose are clearly shown in Figs. 1 and 2.

To facilitate the moving of the blank T against the guide-plate R, a slide W, arranged

at the other end of the dies, may be employed, and this is made with two arms *w*, which move between the parts B B', so as to be out of the line of movement of the die C.

5 While the construction shown is preferred, the invention is not confined to the minor details illustrated, as they may be modified in various ways without departing from the spirit of the invention.

10 Having now described the invention, what is claimed as new, and desired to be secured by Letters Patent, is—

15 1. The combination of two frames relatively movable to and from each other, two longitudinally-arranged shearing-dies, an interposed movable floor carried upon one of said frames, and an upper shearing-die carried by the other frame adapted to operate in conjunction with the adjacent edges of the two 20 longitudinal dies and also operate upon the metal blank immediately above the movable floor.

25 2. The combination of two frames relatively movable to and from each other, two longitudinally-arranged shearing-dies, an interposed movable floor carried upon one of said frames, and an upper shearing-die carried by the other frame adapted to operate in conjunction with the adjacent edges of the two 30 longitudinal dies and also upon the metal blank immediately above the movable floor, and two strippers secured in position above the longitudinal dies and with an intervening space through which the upper shearing-die 35 may operate.

40 3. The combination of two frames relatively movable to and from each other, two longitudinally-arranged shearing-dies, an interposed movable floor carried upon one of said frames, an upper shearing-die carried by the other frame adapted to operate in conjunction with the adjacent edges of the two longitudinal dies and also upon the metal blank 45 immediately above the movable floor, two 50 strippers secured in position above the longitudinal dies and with an intervening space through which the upper shearing-die may operate, and an adjustable guide arranged above the longitudinal dies and to one end 55 thereof beyond the upper shearing-die.

55 4. The combination of two frames relatively movable to and from each other, two longitudinally-arranged shearing-dies, an interposed movable floor comprising a vertically-movable block, springs to elevate the said block and bolts to limit the upward movement thereof carried upon one of said frames, and an upper shearing-die carried by the other frame adapted to operate in conjunction 60 with the adjacent edges of the two longitudinal dies and also upon the metal blank immediately above the movable floor.

65 5. The combination of two frames relatively movable to and from each other, two longitudinally-arranged shearing-dies, an interposed movable floor carried upon one of said frames, an upper shearing-die carried by the

other frame adapted to operate in conjunction with the adjacent edges of the two longitudinal dies that operate upon the metal blank immediately above the movable floor, and two outer upper longitudinal shearing-dies adapted to operate in connection with the outer edges of the longitudinal dies first mentioned.

70 6. In dies for shearing spoke-blanks, the combination of two longitudinal dies B, B, having their outer edges slightly tapering relatively to each other for a portion of their length and in which the adjacent edges of the said two dies are also tapering, upper dies C, I, I, adapted to operate in conjunction with the longitudinal dies B, B, and in which the intermediate die C is tapering in its length to conform to the spaces between the longitudinal dies B, B, and in which the inner cutting edges of the dies I, I, are arranged at angles relatively to each other to conform to the outer cutting edges of the dies B, B.

75 7. In dies for shearing spoke-blanks, the combination of two longitudinal dies B, B, having their lateral edges slightly tapering relatively to each other for a portion of their length and in which the adjacent edges of the said two dies are also tapering, upper dies C, I, I, adapted to operate in conjunction with the longitudinal dies B, B, and in which the intermediate die C is tapering in its length to conform to the spaces between the longitudinal dies B, B, and in which the inner cutting edges of the dies I, I, are arranged at angles relatively to each other to conform to the outer cutting edges of the dies B, B, longitudinal stripper-bars B', B', arranged above the dies B, B, and a spring-actuated floor C' interposed between said dies B, B, and below the die C.

80 8. The combination of dies having longitudinal cutting edges for operating upon sheet-metal blanks, with a guide to register the blank between the dies arranged to one side of but overlapping the cutting edges of the dies longitudinally considered and consisting of a plate lying in alinement with the said cutting edges of the dies and having a series of apertures out of transverse alinement, a corresponding plate fixed relatively to one of the dies having apertures corresponding to those of the guide longitudinally considered but out of transverse alinement with the apertures in the guide transversely considered the said apertures in said guide and plate being in the direction of movement of the dies, guides for the guide-plate to guide it upon the dies, and a removable pin adapted to be inserted through the apertures of the fixed plate and the guide-plate for adjusting the latter in different relative positions on the dies.

85 9. The combination of dies having longitudinal cutting edges for operating upon sheet-metal blanks, with a guide to register the blank between the dies arranged to one end of the cutting edges of the dies longitudinally considered and consisting of a plate lying in

alinement with the said cutting edges of the dies and having a series of apertures out of transverse alinement, a corresponding plate fixed relatively to one of the dies having apertures corresponding to those of the guide longitudinally considered but out of transverse alinement with the apertures in the guide transversely considered the said apertures in said guide and plate being in the direction of movement of the dies, guides for the guide-plate to guide it upon the dies, and a removable pin adapted to be inserted through the

apertures of the fixed plate and the guide-plate for adjusting the latter in different relative positions on the dies.

15

In testimony of which invention I have hereunto set my hand.
